(57) **CLAIM**

The ornamental design for a cap for a medicine container, as shown and described.

DESCRIPTION

FIG. 1 illustrates one perspective environmental view of a cap for a medicine container constructed in accordance with one embodiment;

FIG. 2 illustrates another perspective environmental view of the cap of FIG. 1;

FIG. 3 illustrates a perspective environmental view of the cap of FIG. 1 in a combination with a medicine container and writing implement, shown in broken lines;

FIG. 4 illustrates a perspective environmental view of the cap of FIG. 2 in a combination with a medicine container and writing implement, shown in broken lines;

FIG. 5 illustrates a front elevation view of the cap in FIG. 1;

FIG. 6 illustrates a rear elevation view of the cap in FIG. 1;

FIG. 7 illustrates a left side elevation view of the cap in FIG. 1;

FIG. 8 illustrates a right side elevation view of the cap in FIG. 1;

FIG. 9 illustrates a right side elevation view of the cap in FIG. 2;

FIG. 10 illustrates a top view of the cap in FIG. 1;

FIG. 11 illustrates a bottom view of the cap in FIG. 1;

FIG. 12 illustrates one perspective environmental view of a cap for a medicine container constructed in accordance with another embodiment;

FIG. 13 illustrates another perspective environmental view of the cap of FIG. 12;

FIG. 14 illustrates a front elevation view of the cap in FIG. 12;

FIG. 15 illustrates a rear elevation view of the cap in FIG. 12;

FIG. 16 illustrates a left side elevation view of the cap in FIG. 12;

FIG. 17 illustrates a right side elevation view of the cap in FIG. 12;

FIG. 18 illustrates a right side elevation view of the cap in FIG. 13;

FIG. 19 illustrates a top view of the cap in FIG. 12; and,

FIG. 20 illustrates a bottom view of the cap in FIG. 12.

(Continued)

In the drawings, the broken lines show portions of a cap and a medicine container combined with a writing implement in FIGS. 1 and 2 that form no part of the claim.
